UNITED STATES PATENT OFFICE

HENRY BIANCO, OF BALTIMORE, MARYLAND, ASSIGNOR TO CAMPBELL METAL WINDOW CORPORATION, OF BALTIMORE, MARYLAND, A CORPORATION OF MARYLAND

WEATHER SEAL CONSTRUCTION FOR WINDOWS

Application filed March 22, 1930. Serial No. 437,956.

This invention relates to weather seals for windows of the type in which the jambs have vertical openings through their inner face which lead to enlarged chambers within the jambs and the sashes have plates which extend into these openings, and involves a modification of or improvement upon the construction shown in Campbell Patent No. 1,673,393, issued June 12, 1928. With windows of this type it is customary to construct the sill so that there is an approximately vertical portion or break in the sill about in line with the inside edge of the vertical opening provided for the lower sash. On the room side of such break the sill is ordinarily substantially flat, and at such break the sill drops downwardly so that the lower sash extends down outside of such break. A detailed showing of a sill construction in which this break is particularly apparent is found in Campbell application, Ser. No. 375,384, filed July 2, 1929.

Where the window is exposed to heavy wind pressures as in modern high buildings, there is danger, in the event of a driving rain storm, that water will be driven around the ends of the lower sash plates and run to the flat portion of the sill which extends into the jamb, and then leak through into the room. By my present invention I provide a construction which overcomes this difficulty. Inasmuch as the construction is primarily intended for the lower sash of the window, I have illustrated it only in this connection, but it may also be used in connection with the upper sash if occasion should demand.

My invention may be readily understood by reference to the accompanying drawing which shows a section through a portion of a window jamb and sash of the type referred to. In the drawing the numeral 2 represents the indoors portion of the inner jamb wall which is bent outwardly as shown at 4 to contact with the partition member 6 in the jamb. Attached to the partition member 6 is a baffle 8 which also forms a part of the inner jamb wall. Extending into the space between members 2 and 8 is a sash plate 10 which is here intended to be a part of the lower sash. The line 12 indicates the break of the sill. This

is not shown in detail as it forms no part of my present invention.

Hooked in back of baffle 8 is a member 14 made of flexible material so shaped that it is tensioned toward the rear face of baffle 8 near the opening between the members 2 and 8. The member 14 ordinarily is made to extend the height of the sash. Attached to the sash plate 10, preferably by welding, is an angle 16 extending over toward baffle 8 but leaving a small clearance. A member 18 is hooked over the edge of the sash plate 10 and is bent as shown in the drawing to just clear the projecting edge of angle 16 but with a relatively large clearance between it and the faces of the projecting portion of angle 16. It then is bent to contact once more with the sash plate 10 and has an extension which runs between member 14 and the rear face of baffle 8. It is to be understood that member 18 is connected with sash plate 10 so that it will move vertically with the sash plate, but may move horizontally relative to the sash plate. Such a method of connection is shown in the said Campbell Patent No. 1,673,393.

With this construction, if rain is driven by a high wind against the sash and tries to leak into the jamb, it must follow either one of two courses. If it forces the extending portion of member 18 away from the rear of baffle 8, it cannot get around the sash plate 10, for members 18 and 14 will be in spring contact. There is far more danger of the water following around the face of the sash between the sash and member 18, but in this case the water will enter the enlarged chamber in front of the extended portion of angle 16, where the air will tend to lose its velocity so that a large amount of the water will splatter out against angle 16. Any water that is carried around the free edge of angle 16 will enter the second enlarged space beyond this angle and again be subjected to a decrease in velocity and practically all of the water will be dropped. Such water will run down inside the jamb, but on the outdoors side of the sash plate and so outside the break of the sill, and thus cannot enter the room. If angle 16 were entirely omitted the formation of the enlarged space on the side of the sash

plate would in itself cause a reduction in velocity and accomplish a part of the desired result, but it is much better to have the air current given a definite change in direction 5 within this space, and this is done by the angle iron 16.

What I claim is:

1. In a window of the type having jambs, openings through the inner walls of the 10 jambs, a baffle forming part of the inner jamb wall between such openings, separate enlarged chambers back of such openings and sashes having plates adapted to extend through such openings, and sealing members 15 within the jamb carried by a sash adapted to contact with the rear wall of the baffle and each adapted to contact with a sash plate at two points on the outdoors side of such sash plate and to form an enlarged space adjacent 20 such sash plate between such points of contact.
2. A structure as specified in claim 1, which further includes means for giving air currents which enter such enlarged space a definite change of direction in the horizontal plane.
3. A structure as specified in claim 1 which further includes means which contacts with the sash plate and enters such enlarged space and thereby prevents air currents from passing directly through such enlarged space.

HENRY BIANCO.
